ATTORNEY.

UNITED STATES PATENT OFFICE.

WALTON C. GRAHAM AND JULIUS F. RASMUSSEN, OF DENVER, COLORADO.

METHOD AND MEANS FOR MAKING SHOW CARDS AND THE LIKE.

Application filed April 11, 1922. Serial No. 551,739.

To all whom it may concern:

Be it known that we, WALTON C. GRAHAM and JULIUS F. RASMUSSEN, citizens of the United States, residing at Denver, in the county of Denver and State of Colorado, have invented certain new and useful Improvements in Methods and Means for Making Show Cards and the like, of which the following is a specification.

10 Our invention relates to a method and means for making show-cards, signs, maps and other objects, and its primary object is to provide a simple and convenient method of attaching cut letters and other characters upon a surface in true alinement with each other and at the proper distances apart.

We attain this object by the provision of cut letters, figures and other characters made 20 of paper or other flexible material coated on one side with an adhesive, and formed with detachable extensions which, in edge-to-edge alinement, determine the spaces between the letters in the formation of a word or phrase.

25 In co-operation with these characters, is used a holding element adapted to place the adjoining letters in alinement by engagement with the end-edges of their extensions and provided with means to clamp the same 30 against relative displacement.

An embodiment of the means employed for carrying our invention into practice, has been shown in the accompanying drawings in the several views of which like parts 35 are similarly designated and in which

Figure 1 represents a plan view of the holding element with a plurality of letters in place thereon;

Figure 2, a section on the line 2—2, Figure 40 1;

Figure 3, a similar section showing the first action in the process of attaching the letters on the holder, to the surface of a sign or other object;

45 Figure 4, a similar view illustrating the second step of the process;

Figure 5, an edge view of the sign and one of the letters showing the final step in the process of attaching the letters to a surface, 50 after they have been detached from the holding element;

Figure 6, a face view of the completed sign, drawn to a reduced scale; and

Figure 7, an enlarged face view of two

of the character members of the device in 55 their original condition.

Referring more specifically to the drawings, the reference numerals 2 designate the character members of the device cut or stamped out of paper or other flexible material, and each composed of a body portion 3 cut in the form of a letter or other character and an extension 4 which in the operation, functions as a stub or tab to place the characters in alinement and at the right distances apart.

The character members are coated on their reverse side with an adhesive substance and their bdy portions are detachable from their extensions along lines indicated at 5 in Fig. 70 ure 7 of the drawings.

The holding element consists of a straight-edged rule 6 which in parallel and spaced relation to its edge 8, has an abutment shoulder 7 which in the operation, functions to 75 align the character members as will herein-after be more fully described.

In the construction shown in the drawing the shoulder is formed through the medium of a strip 9 of comparatively narrow 80 width which is secured to the rule by rivets 12 or other suitable fastening means.

Mounted on the strip 9 are a plurality of equidistantly arranged clamping members 10 which project beyond the forward edge 85 thereof to engage with a plate 13 of glass, mica, pyrolin or other transparent material placed between said edge and the corresponding edge of the rule.

The plate is narrower than the space between the edges of the strip and the ruler upon which it is supported and its width is substantially equal to that of the extensions of the character members used in connection with the instrument.

The clamps hereinbefore referred to each consist of a U-shaped blade 14 of resilient metal fastened at one of its ends to the strip 9 and extended beyond the forward edge thereof to engage with the surface of the 100 transparent plate 13.

An upright stud 15 on the strip extends loosely through an aperture in the upper portion of the spring, and a nut 16 on the threaded upper end of the stud bears upon 105 the spring to force its extended portion into clamping engagement with the plate.

The transparent plate may if so desired,

be provided with a graduated scale 17 to facilitate the placement of the letters relative to the center or other given point of the straight edge of the rule, or to permit of wider or narrower spacing of the letters than provided for by their stubs or extensions.

In the operation of our invention, the character members required to form a given word or phrase are placed in the proper order with their stubs or tabs between the clamping plate and the surface of the rule. The contact of the lower edges of the extensions with the abutment shoulder places the characters in alinement, and the engagement 10 of the end edges of the same with each other, spaces the letters at the proper distances apart.

The characters thus arranged are fastened against relative displacement by pressing the 20 resilient clamp-members against the plate through the medium of the nuts, and owing to the similarity in width of their stubs and the plate, the lower edges of their body portions will be in a line coincident with the 25 forward edge of the plate.

In order to fasten the characters in their proper arrangement to the surface of a show-card, map or other object, the rule on which they are held is placed on the surface 30 in a measured position, after which the body portions of the character-members projecting beyond the straight edge of the rule, are pressed to engagement with the surface by means of a suitable tool such as is shown in 35 broken lines at 18 in Figures 3 and 4 of the drawings.

When the letters are fastened by moisture, their gummed sides are wetted before the 40 pressure is applied or in case they are fastened by the application of heat, the tool by which they are pressed to the surface of the sign is heated by any suitable method.

An electrically heated iron of small proportions such as commonly used in laundry 45 work, is well adapted for the purpose.

The engagement of the softened adhesive coatings of the character members with the surface of the card causes the major part of their body portions to adhere thereto, as 50 shown in Figures 3 and 4, it being apparent that their ends at which they adjoin their extensions, are not capable of engaging with the surface until the characters are detached from the holder.

55 This is readily accomplished by drawing a knife or other cutting tool along the straight edge of the clamping plate, thereby severing the characters from their stubs and permitting of removal of the instrument as indicated in Figure 4.

The ends of the letters may now be fastened to the surface by the same means employed to fasten their other portions, as shown in Figure 5, and this final operation 65 completes the work which as shown in

Figure 6, will present an appearance closely resembling that of a hand-painted show card.

An outstanding feature of our invention is that it enables persons unskilled in the art 70 of lettering or designing, to make show cards and other signs which in the form, spacing and alinement of their characters are equal to the best hand-painted work. and it will be apparent that after the letters 75 have been attached to the card, they may be ornamented by shading or illuminations, and that our improved method is therefore productive of results equal in appearance to any style of hand-painting and invariably 80 perfect as to the spacing and alinement of the letters and produced in but a fraction of the time otherwise required.

Having thus described the appliance used in our method of lettering signs, show-cards, 85 maps and other objects, we desire it understood that variations in details of construction and the arrangement of the parts may be resorted to without departing from the 90 spirit of the invention.

The stubs or extensions of the character-members may, for example, be divided from the body portions of the same by perforated or otherwise weakened lines, thereby permitting of their being detached from the 95 characters without the use of a knife or other cutting tool.

Any kind of adhesive can be used to fasten the letters to the mount, the adhesive can be softened by either heat or moisture, and where the last mentioned method is employed, any suitable liquid may be applied to either the gummed surface of the letters or to the surface upon which they 100 are fastened.

It will furthermore be evident that by lengthening the stubs of the character-members so that they extend beyond the straight edge of the rule, the body portions of the same may be fastened on the mount in one 110 operation, and that if so desired, the stubs may be detached from the holding element before they are separated from the fastened characters.

The transparency of the clamping plate 115 of the holding element is a convenience in that it enables the operator to see the arrangement of the stubs relative to each and the abutment shoulder along which they are alined, but it will be apparent that the same 120 result may be attained although perhaps in a less suitable manner by perforating the plate or by notching the edge at which it adjoins the abutment.

What we claim and desire to secure by 125 Letters Patent is:

1. The method of making show-cards and the like, consisting in assembling cut characters into a word or phrase, fastening the assembled characters partially upon a sur- 130

face by an adhesive, then detaching the characters from the means by which they were held in assemblage, and finally fastening the other parts of the characters to the

5 surface.

2. An appliance for making show-cards and the like, comprising in combination, cut character-members each having a gummed body portion and an extension at an end 10 thereof, a rule, and means for holding an assemblage of the character members on the rule by engagement with their extensions and with their body portions projecting beyond an edge of the rule.

15 3. An appliance for making show-cards and the like, comprising in combination, cut character-members each having a gummed body portion and an extension at an end thereof, a rule, a plate parallel to an edge 20 thereof and adapted to engage the extensions of a plurality of character-members assembled on the rule with their body portions projecting beyond said edge thereof, and clamping means co-operating with said 25 plate to hold the members in place on the rule.

4. An appliance for making show-cards and the like, comprising in combination, cut character-members each having a gummed body portion and an extension at an end 30 thereof, a rule, a plate parallel and in spaced relation to an edge thereof, and adapted to engage the extensions of a plurality of character-members assembled on the rule with 35 their body portions projecting beyond said edge thereof, and clamping means co-operating with said plate to hold the members in place on the rule.

40 5. An appliance for making show-cards and the like, comprising in combination, cut character-members each having a gummed body portion and an extension at an end thereof, a rule having an abutment shoulder parallel to an edge thereof, a plate parallel 45 to said edge, adapted to engage the extensions of a plurality of the character-members assembled on the rule in engagement with said shoulder and with their body portions projecting beyond said edge, and 50 clamping means co-operating with the plate to hold the members in place on the rule.

6. An appliance for making show-cards and the like, comprising in combination, cut character-members each having a gummed body portion and an extension at an end 55 thereof, a rule having an abutment shoulder parallel to an edge thereof, a plate parallel to said edge, adapted to engage the extensions of a plurality of the character-members assembled on the rule in engagement

with said shoulder and with their body portions projecting beyond said edge, said plate bearing a graduated scale along its outer edge.

7. An appliance for making show-cards 65 and the like, comprising in combination, cut character-members having gummed body portions and extensions at an end thereof, which are proportioned to space the characters by end-to-end engagement, a rule 70 having an abutment shoulder parallel to an edge thereof, a transparent plate parallel to said edge, adapted to engage the extensions of a plurality of the character-members assembled on the rule in engagement with said shoulder and with their body portions projecting beyond said edge, and clamping means co-operating with the plate to hold the members in place on the rule.

8. An appliance for making show-cards 80 and the like, comprising in combination, cut character-members having gummed body portions and extensions at an end thereof, which are proportioned to space the characters by end-to-end engagement, and an element adapted to hold a plurality of the character members in assemblage, by engagement with their extensions exclusive of their body portions.

9. As a new article of manufacture, a 90 character member adapted to be assembled with other similar character-members into a word or other combination of characters, and consisting of a gummed body portion and a detachable extension at an end of said portion, adapted for end-to-end engagement with a corresponding extension of the body portion on an adjoining character-member.

10. In combination, a plurality of character-members each having separate from the others a gummed body portion and a detachable extension at an end thereof, the extensions of the character members being adapted to space said members in a word or other combination of characters by end-to-end engagement.

11. As a new article of manufacture, a character-member adapted to be assembled with other similar character-members into a word or other combination of characters, 110 and consisting of a gummed body portion cut in the form of a letter or other symbol and a detachable strip at an end of said portion, adapted for end-to-end engagement with a corresponding strip on the body portion of an adjoining member.

In testimony whereof we have affixed our signatures.

WALTON C. GRAHAM.
JULIUS F. RASMUSSEN.
